UNITED STATES PATENT OFFICE.

EDWIN E. ROBERTS, OF HAMILTON, OHIO.

DESIGN FOR A TOY CHAIR.

51,659.

Specification for Design.

Patented Jan. 1, 1918.

Application filed October 19, 1917. Serial No. 197,507. Term of patent 14 years.

To all whom it may concern:

Be it known that I, EDWIN E. ROBERTS, a citizen of the United States, residing at Hamilton, Butler county, Ohio, have invented a new, original, and ornamental Design for a Toy Chair, of which the following is a specification, reference being had to the accompanying drawing, forming part thereof.

The figure is a perspective view of a toy chair, showing my new design.

I claim:

The ornamental design for a toy chair, as shown.

EDWIN E. ROBERTS.

Witnesses:

M. S. BELDEN,
CHARLES VOLLBRECHT.
